UNITED STATES PATENT OFFICE.

WILLIAM SCHILDWACHTER, OF WALWORTH, NEBRASKA.

DRILL-ROD TAP.

1,163,561.

Specification of Letters Patent.

Patented Dec. 7, 1915.

Application filed September 16, 1914. Serial No. 862,040.

To all whom it may concern:

Be it known that I, WILLIAM SCHILDWACHTER, a citizen of the United States, residing at Walworth, in the county of 5 Custer, State of Nebraska, have invented certain new and useful Improvements in Drill-Rod Taps; and I do hereby declare the following to be a full, clear, and exact description of the invention, such as will 10 enable others skilled in the art to which it appertains to make and use the same.

This invention relates to drill and pump rod taps. It is well known that oftentimes when a well is being drilled the drill rod 15 breaks off at various distances below the surface of the ground and an object of this invention is to facilitate the removal of the said broken portion of the drill rod remaining in the ground.

20 A further object of the invention is to prepare the broken portion of the drill rod for removal.

With these and other objects in view, my 25 invention consists in the combination and arrangement of parts as herein described and subsequently claimed.

Referring to the drawing: Figure 1 is a 30 partial sectional view of my device in position to cut threads on the inside of a drill rod section. Fig. 2 is a section on line 2—2 of Fig. 1. Fig. 3 is a section on line 3—3 of Fig. 1.

Referring to the drawing by reference 35 characters, similar characters representing similar parts throughout the several views: 1 represents a casing in which the drill rod 2 is operated and 3 a broken section of the drill rod.

40 My invention comprises means for threading the inside of the broken section 3 and the preferred embodiment thereof includes a hollow cylindrical guide 4 arranged to be lowered in the casing 1 to inclose the drill rod 2. Fixedly secured to the upper end 45 of the guide 4 by screws 6 passing through threaded holes 7 in the guide and threaded holes 8 in the collar member 9 is a downwardly extending conical cutting member 10. On this member 10 are formed cutters 50 11 and 11' for internally threading the broken drill rod section, and on its lower end is formed a bit so that any obstruction which is met in the drill rod may be readily removed. Inasmuch as the drill rods are of 55 various sizes I have seen fit to divide my

cutting members 10 into two sections, an upper section 12 and a lower section 13. The lower section 13 is provided with four cutters 11 and the upper section 12 is provided with five cutters 11'; in fact I can vary the 60 number of these cutters as I see fit, the sole object being, where the diameter of the cutting member 10 is great and is used to thread a larger pipe than the portion of lesser diameter, to provide a great number of cutters 65 so that it will not require so much power to operate as part of the friction is eliminated. On the upper end of the member 10 above the collar 9 is a threaded shank 14 and to this shank is attached a rod 15 70 connected to suitable mechanism at its upper end to rotate the cutter member 10 and thus internally thread the broken drill rod section 3.

In operation when a drill rod has become 75 broken below the surface of the ground the device is lowered in the casing 1 until the guide 4 encircles the broken section 3 and positions the guide 4 axially with respect to the drill rod. Simultaneously the cutter member 10 is inserted in the broken section of the drill rod which engages the conical cutter member at such point as the diameter of the hole in the drill rod will permit. The cutter member 10 is then rotated by suitable mechanism and with it the guide 4 80 which latter member forces the former member to rotate concentrically with the drill rod. This rotating action of the cutter member forms threads on the inside of the broken section of the drill rod by virtue of the cutters 11 or 11'. After the inside of the broken section has been threaded the cutter member 85 is rotated in the opposite direction and withdrawn from the said section and the entire device is lifted from the casing and the portion of the broken drill rod in the ground is ready to be raised.

When it is necessary to thread a drill rod 95 which is inclosed by a large casing I provide the lower end of the guide 4 with one or more collars detachably held to the guide by screws 17, it being understood that each collar extends out farther than the one on which it is mounted so that the member 10 100 may be centered in any size drill rod casing by the use of the appropriate number of collars.

105 From the foregoing it may be seen that I have provided means for threading a broken 110

section of a drill rod internally so that the same may be engaged by a member for raising it from the drilled hole. I have further provided means for the reduction of friction to the minimum when threading large pipes and I have still further provided means for centering the cutter member while threading the drill rod section. I have further provided means for drilling 10 out any obstruction that may be in the drill rod.

I do not wish to be limited to the specific embodiment of my invention shown any further than is necessary by the claims for 15 it is obvious that numerous changes may be made without departing from the scope of the invention.

What is claimed is:—

- 20 1. In a device of the class described to be used in connection with a portion of a drill rod broken off in the ground, means to internally thread said rod, means to position said first mentioned means concentrically with respect to the drill rod, and means 25 to rotate said first mentioned means.
2. In a drill rod tap, a hollow cylindrical guide, a cutter member fixedly mounted within said guide, positioning means on said guide constructed and arranged to position 30 the guide with respect to the work which is to be operated upon.
3. A drill rod tap comprising, a guide, a cutter member mounted within said guide, cutters on the lower portion of said member, a collar on the upper end of said member, means to secure said collar to said guide, a threaded shank extending upwardly from said collar and means engaging said threaded shank to operate the cutter member.
- 40 4. In a device for threading broken drill rods which are located in a tubular casing,

a guide member having collar portions on one end thereof, the lower ends of which are, outwardly flared and having cutting edges adapted to engage the side face of the 45 aforementioned casing to remove foreign matter from the same during the traversing of the casing by the guide, and a tap located within the guide and having thread cutters thereon, and means secured to the 50 tap by means of which it may be rotated.

5. In a device for threading broken drill rods beneath the surface of the ground, a tap having cutters thereon, a guide for moving the drill rod in alinement with the tap, 55 the number of cutters on the lower portion of the tap being greater than the number on the upper portion thereof.

6. In a device for threading broken drill rods beneath the surface of the ground, a 60 guide member having a plurality of collars removably mounted on the lower end thereof, said collars being of various diameters, an inverted conical tap secured within the guide member, and having thread cutters 65 thereon, and means secured to the upper end of the tap for rotating the same.

7. In a device for threading broken drill rods beneath the surface of the ground, a guide member having a plurality of collars 70 removably mounted on the lower end thereof, said collars being of various diameters and having their lower portions flared outwardly and terminating in sharpened edges and a tap secured within the guide member. 75

In testimony whereof, I affix my signature, in the presence of two witnesses.

WILLIAM SCHILDWACHTER.
